UNITED STATES PATENT OFFICE.

EDWARD H. GOVE, OF BIDDEFORD, MAINE.

FLUSHING APPARATUS.

1,263,660.

Specification of Letters Patent. Patented Apr. 23, 1918.

Application filed May 8, 1917. Serial No. 167,319.

To all whom it may concern:

Be it known that I, EDWARD H. GOVE, a citizen of the United States, residing at Biddeford, in the county of York and State of Maine, have invented certain new and useful Improvements in Flushing Apparatus, of which the following is a specification.

This invention relates to improvements in flushing apparatus. It is specially designed for use in connection with water closets. While it is also adapted for use in connection with high-tank closets, it is specially adapted for use in connection with low-tank closets.

Its construction is such as to overcome certain objections which have hitherto been incident to low-tank closets. It is designed to render siphon action certain, perfect, adjustable, adequate and practically noiseless, the latter a feature long sought for, but hitherto unattained in low-tank closets. It does away with the great waste of water and expense of frequent repairs incidental to the under-water valve now in general use. It imparts momentum to the water through an unobstructed waterway, giving a perfect flushing of the bowl. It makes impossible any overflow of the tank with its resulting damage.

In the drawings herewith accompanying and forming a part of this application, Figure 1 is a vertical sectional view of a tank and of my improved flushing apparatus mounted therein, the removable short leg being in section; Fig. 2 is a horizontal sectional view taken on line $x-x$; Fig. 3 is a vertical sectional view of a somewhat modified form of the flushing apparatus, and Fig. 4 is an elevation of the opposite side of the short leg.

The same reference characters indicate like parts in the several figures.

In said drawings 1 is a water tank adapted to contain the flushing apparatus. The flushing apparatus consists of a so-called bell siphon having a long leg 2 adapted to pass through the bottom of the tank and to the bowl and a short leg 3 terminating in the tank. As shown in Fig. 1, the top 4 of the long leg is flaring. The short leg is adapted to be placed down over the long leg and to be seated in a recess 5 formed in a flange 6 integral with the long leg on the back and sides thereof and it may be supported against backward movement by a bar 7. The short leg may be made of any suitable ma-

terial and the upper end 8 is contracted and the lower end 9 is formed at the front vertically in the arc of a circle. Pivotedly mounted in a bearing 10 on the front of the long leg 60 is a device for starting siphon action. This consists of a pivoted piston made in two members, one 11 fixed on a pivot 12 mounted in the bearing and the other or outer member 13 pivotally attached to the former by pivots, 65 14 in projecting arms 15, the two members being of the same width and together being of the same length as the short leg and when extended filling the enlarged or curved part of the short leg with a close fit. The 70 pivot 12, on which the piston is mounted, is provided with a crank 16, by means of which the piston may be raised. When the tank is filled to the proper height, which is just below the open end of the long leg, the apparatus 75 is ready for use. The two members of the piston are then extended at or near the lower end of the short leg. When raised it lifts a body of water in the short leg which passes over into the upper end of the long 80 leg and siphon action begins. As soon as siphon action begins an upward current is induced in the short leg which swings the outer member upwardly on its pivot and allows free passage of water from the tank 85 up through the short leg and over into the long leg. The inner member of the piston is provided with a stop 17 which limits its upward movement beyond a point where gravity would cause it to fall back into down 90 position automatically when power is removed, and the outer member is eccentrically pivoted to the inner member so that when in down position it will automatically by gravity assume an extended position, stops 18 95 limiting the turning movement of the outer member relative to the inner member. One side of the short leg is provided with a recess 20 to allow it to seat down over the crank arm and make a tight fit. The short 100 leg is adapted to be locked in position relative to the long leg by a latch 21 pivotally attached to one leg and adapted to engage a pin 22 on the other leg. To adjust the amount of water to be delivered at each 105 flushing, I affix a pipe 23 to the upper end of the short leg and provide its lower end with a vertically adjustable section 24 which will let air into the short leg as soon as the water in the tank falls below the lower end 110 of the pipe wherever it may be adjusted.

In Fig. 3 I have illustrated the application

of my apparatus to a siphon of ordinary construction except that the lower end of the short leg is similar to that shown in Fig. 1. Its operation, however, is substantially the same as in the former case.

I claim:

1. In a flushing apparatus, a tank, a siphon having a long leg and a short leg the lower front end of which is in the form of a segment of a circular cylinder having a horizontal axis and a piston pivotally mounted in the axis of the cylinder, said piston being divided transversely into two parts of the same width and pivotally joined together.
- 10 2. In a flushing apparatus, a tank, a siphon having a long leg and a short leg the lower front end of which is in the form of a segment of a circular cylinder having a horizontal axis and a piston pivotally mounted in the axis of the cylinder, said piston being divided transversely into two parts of the same width and pivotally joined together, the pivot point of the outer part being spaced apart from the end adjacent the inner part.
- 20 3. In a flushing apparatus, a tank, a siphon

having a long leg and a short leg the lower front end of which is in the form of a segment of a circular cylinder having a horizontal axis, a piston pivotally mounted in the axis of the cylinder, said piston being divided transversely into two parts of the same width and pivotally joined together, and means for limiting the upward movement of the piston to a point where gravity will cause it to return down automatically when power is removed.

30 4. In a flushing apparatus, a tank, a siphon having a long leg and a short leg the lower front end of which is in the form of a segment of a circular cylinder having a horizontal axis, a piston pivotally mounted in the axis of the cylinder, said piston being divided transversely into two parts of the same width and pivotally joined together, means for limiting the upward movement to a point where gravity will cause it to return down automatically when power is removed and means for limiting the upward movement of the outer part relative to the inner part.

40 In testimony whereof I affix my signature.
EDWARD H. GOVE.
